US00D774082S

(12) **United States Design Patent** (10) **Patent No.:** **US D774,082 S**
(45) **Date of Patent:** **** Dec. 13, 2016**

(54) **DISPLAY SCREEN OR PORTION THEREOF
WITH ICON**

(71) Applicant: **Apple Inc.**, Cupertino, CA (US)

(72) Inventor: **Chanaka Karunamuni**, Cupertino, CA (US)

(73) Assignee: **Apple Inc.**, Cupertino, CA (US)

(**) Term: **14 Years**

(21) Appl. No.: **29/511,886**

(22) Filed: **Dec. 15, 2014**

Related U.S. Application Data

(63) Continuation of application No. 29/445,391, filed on Feb. 11, 2013, now Pat. No. Des. 720,772, which is a continuation of application No. 29/393,470, filed on Jun. 4, 2011, now Pat. No. Des. 676,058.

(57)

CLAIM

The ornamental design for a display screen or portion thereof with icon, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a display screen or portion thereof with icon showing the claimed design.

The broken lines in the Figure show a display screen or portion thereof, and form no part of the claimed design.
